UNITED STATES PATENT OFFICE.

EDWIN THACHER, OF PITTSBURG, PENNSYLVANIA.

BRIDGE-TRUSS.

SPECIFICATION forming part of Letters Patent No. 242,396, dated May 31, 1881.

Application filed July 16, 1880. (No model.)

To all whom it may concern:

Be it known that I, EDWIN THACHER, a citizen of the United States, residing at Pittsburgh, Allegheny county, in the State of Pennsylvania, have invented useful Improvements 5 in Combination and All-Iron Bridge-Trusses, of which the following is a specification.

By combination-truss is meant one in which the top chord and end struts are wood, the 10 bottom chord, ties, and suspenders iron, and the intermediate struts either wood or iron.

The object of my invention is to overcome 15 the defects common to a greater or less extent in all forms of triangular or quadrangular truss now in use, of which the following may be named:

First. In all combination quadrangular trusses (trusses containing quadrangles the sides of which are all connected with each 20 other and with diagonals that cross each other and join opposite angles) both main ties and counter-ties are affected by temperature, the latter frequently to the extent of half their breaking strength.

Second. In double and triple intersection trusses there is ambiguity of strain—that is to say, there are no means of finding what the 25 actual strain on a member is. This is also true of any truss in which a weight can find its way in more than one direction to the masonry or points of support.

Third. Counter-ties are liable to be overstrained in adjustment by unskilled workmen.

Fourth. Triangular trusses have sometimes 35 tension and at other times compression on braces near the center. When the greater of these strains is compression, a wooden brace with iron tensile connections is generally used in combination-trusses. If, on the other hand, 40 tension is much the greater strain to which the brace is subjected, flat bars connected with zigzag bracing are generally used. Both of these expedients are objectionable, the former owing to strains by temperature on the connections and the latter to frequency of damage by handling.

Fifth. Both quadrangular and triangular trusses as usually constructed have each end of the floor-beam or cross-girder on which the 45 track or flooring rests supported by two suspenders, which are short links or bars con-

necting the end of the floor-beam to joint above. These suspenders are generally a considerable distance apart, in combination triangular, two feet six inches being not uncommon. The reason of this is, that each joint is made up strut, tie, chord, and floor-beam suspender. The thrust coming down the strut from other parts of the truss, together with the weight suspended at the floor-beam, is taken by the tie 55 and carried on toward the support. Now, in order to avoid a very large pin at the joint or excessive bending strain upon it, it is necessary that the connection of floor-beam suspender on the pin be made near or in contact 60 with that of the tie, the latter being in pairs, and from the nature of the truss cannot be brought close together. The deflection of a floor-beam when the load comes upon it causes an excess of weight to be thrown upon the inner suspender, and relieves the outer one to a 65 corresponding extent. This unequal strain is conveyed by the suspender through the pin on which it hangs to the various members of the truss, whose unequal extension or compression gives rise to distortion and cross-strains.

Sixth. Adjustable counter-ties in quadrangular trusses and trussed ties in triangular trusses are very expensive in workmanship.

Seventh. The large variation in top-chord sections in the different panels of most combination-trusses renders iron packing difficult and expensive—that is to say, the strain on the chord increases rapidly toward the center, 85 where a much larger section of timber is required than at the ends; and as the chord, as a whole, is always made of uniform width and depth from end to end, the variation in section can only be made by allowing much larger 90 spaces between the sticks composing the chord at the end than at the center. In order to make these sticks act together and about the axis of the chord as a whole, it is necessary to connect them by keys or packing, by which 95 any strain on one stick will be transmitted through the keys to all the other sticks of which the section is composed; otherwise each stick will bend about its own axis and its strength be thereby much diminished. If the spaces 100 between the sticks are small, the required connection can be easily and cheaply made by

means of lightcast-iron keys ; but if the spaces are large the keys become massive, and their effectiveness at best is much impaired. Wooden keys are generally used in these bridges, but at the expense of greatly-reduced durability, for it is a well-known fact that wood in contact with wood soon decays, but that wood in contact with iron is not thus affected.

8 Eighth. In quadrangular trusses the sudden change of strain from counter-tie to opposite main tie, or the reverse, as a train passes over, and the consequent racking of parts, is very injurious.

5 My improved truss can be made free from the foregoing objections.

It consists of a primary triangular truss composed of top and bottom chords, together with a web of struts and ties, arranged in the form of triangles, free to change figure from the effects of temperature. The center ties extend each over a greater number of panels than any strut, over not less than two, and over not more than the number in half-span less one. The panel-points intermediate between the tops of the center ties, and not at joints of the primary truss, are supported by vertical suspenders, or partially supported by pairs of inclined suspenders, from the top of the center strut, and the balance supported from the outermost limits of suspension. The inclined suspenders are connected with each other, but have no fixed connection with the bottom chord, nor with the center ties at intermediate points of intersection.

35 Figures 1 to 5, inclusive, represent side elevations of bridge-trusses embodying my invention ; and Fig. 6 represents, in detail, a side elevation of intermediate panel-point, D.

In Figs. 1, 2, and 3 the top and bottom chords, together with the members F A, A B, and B C, constitute the primary truss. In Figs. 4 and 5 it consists of the same members, with the addition of the two diagonals between A F and the end of span.

45 All parts not specified above as belonging to the primary truss are suspended from it or used to support intermediate panel-points. A A may be called the limit of suspension.

A B are the center ties, connected with the top chord at A and with the bottom chord at B.

50 C B is the center strut, either vertical, as in Figs. 1 and 3, or sloping toward the end, as in Figs. 2 and 4, or toward the center, as in Fig. 5. The struts may be vertical or inclined, as best fulfills the requirements of any particular case.

In Figs. 1, 2, 3, and 4 the center ties meet in the bottom chord. In Fig. 5 the center struts meet in the top chord.

60 E E are intermediate panel-points, supported by the vertical suspenders C E from the top of the center strut, C B.

D D are intermediate panel-points, supported by inclined suspenders directly or indirectly from the points A and C of the primary truss. These suspenders are in pairs, connected with

each other at D ; but they have no fixed connection with the center ties, A B, nor with the bottom chord. In Fig. 6 the broken bar below D is the chord, supported, as shown by 70 the suspenders, by means of a stirrup attached to the pin above. It may, however, be done, if desired, by means of a seat on the floor-beam below ; but whatever method is adopted, the joint at D must be left free to move longitudinally unrestrained by the chord. These panel-points may each be supported by pairs of inclined suspenders A D and D C, leading directly from them to the points A and C of the primary truss, as shown ; or some of them may 80 be thus supported and others of them as before described.

If the length of span permits, the center ties may each extend over four or more panels, and a greater number of intermediate panel-points 85 be suspended. A A are the limits between which intermediate suspended panel-points aid in overcoming reversed strains in the center braces, and the center ties may always extend over a sufficient number of panels to ac- 90 complish this object when desired.

The weight at any intermediate panel-point, D, is conveyed by the inclined suspenders to the joints A and C of the primary truss in proportions inversely as its horizontal distance 95 from those joints. The part going to C increases the compression in the center strut, C B, as does also the weight from any intermediate panel-point, E, conveyed through vertical suspenders to the same point. Any compression 100 in the center strut due to intermediate suspended panel-weights gives tension on the center ties on both sides of the center, and opposes reversed strains in the center braces due to partial rolling loads. The only panel-points on 105 which rolling load either side of the center can tend to produce reversed strains in the center ties are those at A, or between those points and the truss-supports. The compression in the center strut and tension in the center tie 110 increases as the points A are moved toward the end of span, and the distance between these points can, if desired, always be made sufficient to overcome all reversed strains in the center braces. Any panel load produces 115 compression in the top chord and tension in the bottom chord.

In Figs. 1 and 3 the maximum strain in either chord, which occurs when all joints are loaded, is uniform throughout its length, and 120 in all the trusses the maximum strains in the different panels of the top chord are so nearly uniform that in combination-bridges the section could be made uniform without material increased cost.

125 The bottom lateral system may consist of longitudinal and diagonal tension-rods connected with transverse floor-beams, which act as the struts of the system ; or it may consist of transverse struts and diagonal tension - rods 130 connected with longitudinal floor-beams suspended from the panel-points.

From the preceding description it will be understood how the advantages which my truss possesses over the prevailing styles previously claimed, but not described, are gained.

5 As there are no confined quadrangles, and as no wooden braces having iron tensile connections need be used, temperature strains can be avoided.

As the suspenders act independent of the chord at D, the weight at those points can reach the joints A and C of the primary truss in no other way or manner than as described, and as the primary truss consists of a single system of triangular figures, a weight at any joint 15 of it can go in but one way to either point of support; consequently there can be no ambiguity.

As the length of any one or more of the members of the primary truss or of the suspenders 20 can be changed and the work still come together as readily as before, adjustments are not called for.

As the pairs of inclined suspenders at D and of center ties at B can be placed as near 25 together as desired and in contact with the floor-beam suspender between them, the latter can be made of a single bar at the center of pin without increase of cost.

The vertical suspenders C E can be made a 30 single bar passing through the floor-beam if the latter is of wood, or in pairs connected by pin at E, with a single loop-suspender between them connected with the floor-beam, if an iron floor-beam with a single web is used.

35 As in all the figures a top chord of uniform section would be used in combination-bridges, and the spaces between the chord-sticks be made uniform and as small as desired, packing blocks or keys of iron can be used at a 40 minimum expense.

My improved truss is more economical in workmanship than others, owing to the shorter and smaller pins, the absence of sleeve-nuts or 45 adjustments of any kind, and its freedom from

zigzag bracing. It is also fully as economical 45 in material as any of the prevailing styles.

As there are no adjustments to get out of order, it requires little or no superintendence after it is once erected, and as every part is strained under all conditions of load, and as 50 no distortion can change this relation of parts, less repairs will be required and a longer life insured than in counterbraced forms. It has all the advantages without the disadvantages found in most of the trusses now in use. 55

I claim as new and desire to secure by Letters Patent—

1. A bridge-truss consisting of a primary triangular truss, composed of top and bottom chords, and a web of struts and ties arranged 60 in the form of triangles free to change figure from the effects of temperature, substantially as set forth, the center ties extending each over a greater number of panels than any strut, over not less than two, and over a number not 65 exceeding the number in half-span less one, the panel-points intermediate between the tops of the center ties, and not at joints of the primary truss, being supported by vertical suspenders, or partially supported by pairs of inclined suspenders, from the top of the center strut, and the balance from the outermost limits of suspension, said inclined suspenders being also 70 connected with each other, but having no fixed connection with the bottom chord, nor with the 75 center ties at intermediate points of intersection.

2. Inclined suspenders in combination with a triangular truss having a bottom chord always in tension, which support the weight of 80 that chord without having any fixed connection with it by means of a stirrup attached to the pin above, substantially as set forth and described.

EDWIN THACHER.
